CLAIM

The ornamental design for a toy collapsible structure, as shown and described.

DESCRIPTION

FIG. 1 is a front elevational view of a toy collapsible structure showing our new design;

FIG. 2 is a side perspective view thereof;

FIG. 3 is a view similar to FIG. 2 showing the other side perspective thereof; and,

FIG. 4 is a top plan view thereof.

The bottom and rear sides of the design are planar and unornamented except for the openings in the rear wall as shown in FIG. 2.

1 Claim, 4 Drawing Sheets
